TION OF ILLINOIS.

SERVICE-METER CIRCUITS.

1,026,151.

Specification of Letters Patent. Patented May 14, 1912.

Application filed November 7, 1907. Serial No. 401,068.

To all whom it may concern:

Be it known that we, HIRAM D. CURRIER, of Chicago, Cook county, Illinois, and GEORGE WOLF, of New York, New York county, New York, citizens of the United States, have invented a certain new and useful Improvement in Service-Meter Circuits, of which the following is a full, clear, concise, and exact description.

10 Our invention relates to a telephone service meter, and its object is to provide an improved organization of circuits and apparatus whereby a given connection cannot be registered more than once.

15 A further object is to provide means whereby, after a connection has once been registered, a subsequent attempt to register the same connection will cause the operation of a signal and indicate such fact to 20 the operator.

One feature of our invention consists in an arrangement of circuits and apparatus whereby more than a single registering of a given connection on either the line or position meter is rendered impossible.

25 A further feature of our invention is the arrangement whereby a guard signal is caused to operate if an attempt is made to register a given connection more than once.

30 More specifically, our invention consists in an arrangement of circuits adapted to be associated with the cord circuit by the depression of the registering key, whereby, if the service meter is in its unoperated position, a call will be registered on the line service meter, and also on the position meter; but, after such registering has once been effected, a subsequent depression of the registering key will cut the position meter 35 out of circuit and preferably will also close a circuit through a guard lamp or other warning signal.

We will describe our invention more particularly by reference to the accompanying 40 drawing, which is a diagram illustrating the preferred embodiment thereof.

The telephone exchange system illustrated is in general of a well-known type, and hence we shall give a detailed description 45 of only such parts as embody our invention, or are more directly related thereto. Each line has at its substation A the usual telephone apparatus. The telephone line includes at the central office the usual line re- 50 lay C, controlling the line signal l, and is

connected by way of the contacts of the usual cut-off relay D to a common battery B. The winding of relay D has a resistance of, say, thirty ohms, and is included, as usual, in a conductor 3, which connects with the test ring a to ground. The electromagnet E of the line meter M is placed in multiple with the cut-off relay D. Said magnet E has a high-resistance winding e, as, for example, of five hundred ohms, and also a normally-open low resistance locking winding e' of, for example, forty ohms, adapted to be closed in the attracted position of the armature e² in the operation of the line meter M.

55 The cord conduit is of a well-known type, with the exception that a resistance R of, for example, one hundred ohms, is included in the third strand 4, said resistance being normally short-circuited through the switch K. The improvement in which our invention more particularly consists lies in the circuit adapted to be connected with the third strand by the key or switch K for controlling the operation of the service 60 meter M. The connection register switch K when closed is adapted to bridge a local circuit to ground from the point 8 in the third strand of the cord circuit. Said local circuit includes a grounded battery B' of 65 higher voltage than the common battery B. We have found, with the values assigned to the various resistances as indicated, and with the usual twenty-four-volt common 70 battery B, that the battery B' of from thirty-four to thirty-eight volts gives satisfactory results. In the lead from the battery B' to the contact 5 of the service meter key K, there are two relays, F and G of, for example, half an ohm and ten ohms resistance, respectively. The relay G is preferably a double-spool telegraph relay, such as shown. The electromagnet H, which controls the position meter M', is in a shunt of the relay G, said shunt circuit being normally open at contact 75 f, controlled by relay F. The armature g of relay G is included in said shunt circuit, and when attracted is adapted to open said shunt circuit at back contact 6, and to close a front contact 7. A current sufficient to operate the relay G to close contact 7 will thus close a circuit from the grounded battery B' through relay F, contacts f and 80 7, and guard lamp s', for the purposes herein-

after set forth. The magnet H in the attraction of its armature *h* operates the registering mechanism of the position meter M', and also closes a local circuit including the 5 common battery B and a lamp or other signal *s*, thus indicating the operation of said meter. The resistance R is sufficiently high as, for example, a resistance of one hundred ohms, to lessen the current from the high 10 voltage battery B' dividing at the point 8 and seeking a path to ground through the battery B. The resistance R is not so high, however, but that it permits a sufficient flow of current from the battery B, during the 15 movement of the switch K from its back to its front contact, to hold the armature of the cut-off relay D in its attracted position and to maintain the locking circuit *e'* in its closed condition after the meter M has operated.

20 The operation of the system is as follows: The operator having noticed, through the operation of the line lamp *l*, that a subscriber is making a call for a connection, in answering, inserts the plug *p* in the answering jack *j* of the line. A circuit is thus completed from battery B through the third strand 4, ring *a*, conductor 3, relay D to ground, resulting in the operation, in the usual manner, of the cut-off relay D. The 25 magnet E, in multiple with relay D, is not operated, owing to the high resistance of its winding *e*. The operator proceeds in the usual way to obtain the called subscriber, and if successful depresses the key K to 30 operate the service meter M of the calling line. When said key is depressed the relay F operates immediately, thereby preventing the operation of the relay G by closing the shunt circuit about the same. Said shunt 35 circuit includes the electromagnet H, but said magnet does not as yet operate, owing to the high resistance in the circuit thus closed. In response to the initial flow of current from battery B', the magnet E operates, thereby closing its low resistance locking winding *e'*. As a result of this reduction of resistance in its circuit, the magnet H operates and lights the lamp *s*, thereby indicating that both the line and position 40 meters have operated. The armature *e²* of the magnet E will be held by the locking winding *e'* in its actuated position even when the key K is released, as long as the plug *p* remains inserted in the jack *j*. If 45 now the operator should again depress the key K, the meter M being already in operated position, there would be no second operation thereof. The low resistance winding *e'*, in this case, moreover, would allow a considerable flow of current, permitting the operation of relay G, as well as relay F, and thus open contact 6 and close contact 7. As 50 a result, the magnet H is cut out of circuit and its operation prevented, and the circuit of the guard lamp *s'* is closed at con-

tacts 7 and *f*. The lighting of the guard lamp would indicate to the operator that the connection had already been registered. It is obvious that upon the withdrawal of the plug at the termination of the call, the 70 parts will be restored to their normal positions.

It will be seen that our invention provides means whereby after the position and line meters have operated to register a given connection, all subsequent attempts to operate said meters for the same connection will be non-effective, and will result merely in the 75 operation of a guard lamp to indicate the fact that the connection had been previously 80 registered.

We claim:

1. In a telephone system the combination with a telephone line, of a central office connection switch, an electromagnetically operated line meter having a circuit controlled at one point by said connection switch, a local circuit including an independent source of high potential current and an electromagnetically operated position meter, a connection register switch for completing said local circuit through said line meter and thereby operating said meters, a magnet energized upon the operation of said connection register switch while said line meter is in its operated position, and a device operated by said magnet when excited directly controlling said position meter to prevent the operation thereof. 85

2. In a telephone system, the combination with a telephone line, of a central office connection switch, an electromagnetically operated line meter having a circuit controlled at one point by said connection switch, a local circuit including an electromagnetically operated position meter, a guard lamp associated with said local circuit, a connection register switch for completing said local circuit through said line meter and thereby operating said meters, a magnet energized 100 upon the operation of said connection register switch while said line meter is in its operated position, and a device operated by said magnet when excited directly controlling said position meter to prevent the operation thereof and to operate said guard signal. 105

3. In a telephone system, the combination with a telephone line, of a central office connection switch, an electromagnetically-operated line meter having a circuit controlled at one point by said connection switch, a local circuit including an electromagnetically-operated position meter, a connection register switch for completing said local circuit 120 through said line meter and thereby operating both of said meters, means in the circuit of said meters for increasing the flow of current in said circuit upon the operation of said meters, and a relay responsive only 125 130

to said increased flow of current and by its operation preventing more than a single operation of said position meter for a given connection.

- 5 4. In a telephone system, the combination with a telephone line, of a central office connection switch, an electromagnetically-operated line meter having a circuit controlled at one point by said connection switch, a local 70
10 circuit including an electromagnetically-operated position meter, a connection register switch for completing said local circuit through said line meter and thereby operating both of said meters, a guard signal, 75
15 means in the circuit of said meters for increasing the flow of current in said circuit upon the operation of said meters, and a relay responsive only to said increased flow of current and by its operation preventing 80
20 more than a single operation of said position meter for a given connection, and for operating said guard signal in response to a further closure of said connection register switch.
- 25 5. In a telephone system, the combination with a telephone line, of a central office connection switch, a line meter having a circuit adapted to be completed by said connection switch, a local circuit including a high 90
30 resistance relay, a low resistance relay and an independent battery in series with one another, a shunt of said high-resistance relay controlled by said low resistance relay, a position meter included in said shunt circuit, and a connection register switch for completing said local circuit through said line meter.

6. In a telephone system, the combination with a telephone line, of a central office connection switch, a line meter having a circuit adapted to be completed by said connection switch, a local circuit including a high resistance relay, a low resistance relay and an independent battery in series with one another, a shunt of said high resistance relay controlled by said low resistance relay, a position meter included in said shunt circuit, a switch in said shunt circuit controlled by said high resistance relay, for cutting said 105
45 position meter out of circuit, and a connection register switch for completing said local circuit through said line meter.

7. In a telephone system, the combination with a telephone line, of a central office connection switch, a line meter having a circuit adapted to be completed by said connection switch, a local circuit including a high resistance relay, a low resistance relay and an independent battery in series with one another, a shunt of said high resistance relay controlled by said low resistance relay, a position meter included in said shunt circuit, a switch in said shunt circuit, controlled by said high resistance relay for cutting said 120
55 position meter out of circuit, a guard lamp
60 other, a shunt of said high resistance relay controlled by said low resistance relay, a position meter included in said shunt circuit, a switch in said shunt circuit, controlled by said high resistance relay for cutting said
65 position meter out of circuit, a guard lamp

arranged to be included in the circuit upon the operation of said last-named switch, and a connection register switch for completing said local circuit through said line meter.

8. In a telephone system, the combination 70 with a telephone line, of a central office connection switch, an electromagnetically-actuated line meter having a circuit adapted to be completed by said connection switch, the actuating magnet of said meter being 75 provided with a high resistance operating winding and a low resistance locking winding, a local circuit including a high resistance relay, a low resistance relay and a high potential battery in series with one another, 80 a shunt of said high resistance relay controlled by said low resistance relay, a position meter included in said shunt circuit, a switch in said shunt circuit controlled by said high resistance relay, for cutting said 85 position meter out of circuit, a guard lamp arranged to be included in the circuit upon the operation of said last-named switch, and a connection register switch for completing said local circuit through said line 90 meter.

9. In a telephone system, the combination with a telephone line, of a central office plug and cord circuit, a line meter having a circuit adapted to be completed by said plug and cord circuit, a normally short-circuited resistance in the third strand of said cord circuit, a local circuit including a high resistance relay, a low resistance relay and a high potential battery in series with one another, a shunt of said high-resistance relay controlled by said low resistance relay, a position meter included in the shunt circuit, and a connection register switch arranged for bridging said local circuit to ground 105 from a point in the third strand of said cord circuit between said resistance included therein, and the plug.

10. In a telephone system, the combination with a telephone line, of a central office plug and cord circuit, an electromagnetically-actuated line meter having a circuit adapted to be completed by said plug and cord circuit, the actuating magnet of said meter being provided with a high resistance operating winding and a low resistance locking winding, a normally short-circuited resistance in the third strand of said cord circuit, a local circuit including a high resistance relay, a low resistance relay and a high potential battery in series with one another, a shunt of said high resistance relay controlled by said low resistance relay, a position meter included in the shunt circuit, a switch in said shunt circuit controlled by said high resistance relay, for cutting said position meter out of circuit, a guard lamp arranged to be included in the circuit upon the operation of said last-named switch, and a connection register switch ar- 110

- ranged for bridging said local circuit to ground from a point in the third strand of said cord circuit between said resistance included therein, and the plug.
- 5 11. In a telephone system, the combination with a telephone line, of a central office connection switch, an electromagnetically operated line meter having a circuit controlled at one point by said connection 10 switch, a local circuit including an independent source of high potential current and an electromagnetically operated position meter, a connection register switch for completing said local circuit through said 15 line meter and thereby operating said meters, a relay energized upon the operation of said connection register switch while said

line meter is in its operated position, and contacts controlled by said relay included in said local circuit.

20

In witness whereof, we hereunto subscribe our names this 17th day of October A. D., 1907, and 21st day of October A. D., 1907, respectively.
